UNITED STATES PATENT OFFICE.

SAMUEL STIMMEL, OF NEW YORK, N. Y.

CONTROL MECHANISM FOR POWER-HOISTS.

1,245,522.

Specification of Letters Patent.

Patented Nov. 6, 1917.

Application filed October 21, 1916. Serial No. 126,835.

To all whom it may concern:

Be it known that I, SAMUEL STIMMEL, a citizen of the United States of America, residing at New York city, county and State 5 of New York, have invented certain new and useful Improvements in Control Mechanism for Power-Hoists, of which the following is a full, clear, and exact description.

10 This invention relates to improvements in power-hoists, the object being to provide a mechanism of this nature which is particularly well adapted for application to a combined motor-truck and trailer to raise 15 or tilt the body of the trailer. My improved power-hoist is arranged for operation by the motor of the truck, special means being provided to disconnect the hoist from the driving-shaft of the truck when 20 the body of the trailer has been raised a predetermined distance.

One of the features of my invention is a specially arranged mechanism whereby the automatic throw-out mechanism can be disconnected from the hoist to permit said 25 hoist to rotate continuously, or to be stopped at will.

While my improved hoist is herein illustrated as applied to a motor-truck and operated by the motor thereof, it is not limited to such use, as it can be used as a hoisting means for general purposes, but it is particularly well adapted for use in connection with a motor-truck and trailer having 35 a tilttable body.

I will now proceed to describe my invention in detail, the essential features of which will be summarized in the appended claims, reference being had to the accompanying 40 drawings, forming part hereof; wherein—

Figure 1 is an enlarged plan view of my improved hoisting device, a portion of the truck-frame and driving shaft being also shown;

45 Fig. 2 is an enlarged sectional detail view, the section being taken on a line 2—2 in Fig. 1;

Fig. 3 is a similar view, the section being taken on a line 3—3 in Fig. 1;

50 Fig. 4 is an enlarged sectional detail view, the section being taken on a line 4—4 in Fig. 1;

Fig. 5 is an enlarged sectional detail view 55 of the throw-out mechanism, the section being taken on a line 5—5 in Fig. 3;

Fig. 6 is a sectional view, the section be-

ing taken on a line 6—6 in Fig. 5, certain parts being illustrated in elevation;

Fig. 7 is an enlarged sectional detail view showing the jack-shaft which carries the 60 sliding gears for operating the hoist; a portion of the engine-shaft, which carries the driving gear for the hoist, being also shown;

Fig. 8 is a cross-sectional view thereof, the section being taken on a line 8—8 in 65 Fig. 7;

Fig. 9 is a sectional plan view of the mechanism illustrated in Fig. 7, the section being taken on a line 9—9 in Fig. 7; and

Fig. 10 is a diagrammatic side view of a 70 motor-truck and trailer having my improved hoist applied thereto.

Referring to Fig. 10, a motor-truck is indicated by A and its trailer by B, said trailer including a body C carried by a 75 framework D having wheels E (one only being shown). As herein illustrated, the body C is hinged to the framework D at 11 and is arranged to be tilted upwardly, at the forward end thereof, by a lever 12 pivoted 80 at 13 to the framework D. One end of the lever 12 carries a roller 14 which bears against the under surface of the bottom of the body C. The opposite end of the lever 12 is connected by a cable or chain, indicated by 15, to the hoisting device F. When the lever 12 is operated, the body C will be tilted up at its forward end and dump the load carried thereby. The means herein shown for elevating or tilting the body C, 90 is an arbitrary arrangement selected for illustration only.

My improved hoisting device F is mounted on the frame 16 of the truck and is operated when required by the driving-shaft 95 17, to which I secure a driving pinion 18. Adjacent the driving-shaft 17, I mount a jack-shaft 19 (see Fig. 7), said jack-shaft being supported by brackets 20 which depend from a bed-plate 21 secured to the 100 frame of the truck. At one end the shaft 19 is provided with a sprocket-wheel 22 which, by means of a chain 23 (Fig. 1), operates a counter-shaft 24 located on the upper surface of the bed-plate 21, the shaft 24 105 being provided with a sprocket-wheel 25 to be engaged by the chain 23.

Upon the shaft 19, I slidably mount a sleeve 26 which is rotatably connected to the shaft 19 by a feather or spline 27. To 110 the sleeve 26, I secure gears 28 and 29; the gear 28, when meshed with the gear 18, will

operate the hoisting device to wind up the cable 15. The gear 29 coöperates with an intermediate gear 30 to reverse the motion or movement of the hoisting-drum.

- 5 The intermediate gear 30 is carried by a bracket 31 extending from a housing 32 through which the sleeve 26 loosely passes, that is to say, the sleeve 26 rotates within the housing 32.
- 10 To prevent the housing 32 from rotating with the sleeve 26, I provide same with an arm 33 having a bearing 34 which slidably engages a rod 35 carried by arms 36 and 37 which extend from the bearings 20.
- 15 To shift the sleeve 26, to cause either the gear 28 or gear 30 to mesh with the gear or pinion 18, I provide the housing 32 with a post 38 carrying a pin 39 engaging the slot 40 in the arm 41 of a gear shifting mechanism.

To cause the hoist to wind up the cable 15, the sleeve 26 will be moved to cause gears 18 and 28 to mesh. To cause the hoist to unwind the cable 15, the housing 32 will be moved to cause the gears 18 and 30 to mesh. When the arm 41 of the shifting device is in a vertical position, the transmission gears 28, 29 and 30 will be in neutral position. At such a time the gear 18 will be positioned between the gears 28 and 30 and out of mesh with both; hence to mesh the gears 18 and 28 the sleeve 26 will be moved toward the right in Fig. 10, and to cause the gears 18 and 30 to mesh the sleeve 26 will be moved toward the left.

The gear shifting device consists of a shaft 42, which carries the arm 41, the shaft 42 being mounted in bearings 43 and 44 (Fig. 1). One end of the shaft 42 carries arms 44^a and 45, the arm 44^a being used to shift the sleeve 26 manually, the arm 45 being connected by a link 46 to an automatic device to move the sleeve 26 to neutral position at the end of a substantially complete revolution of the drum of the hoisting device.

The operation of the hoisting device either forward or backward is instituted by operating the sleeve 26 to the right or left by means of the arm 44^a and other elements of the shifting device.

Motion is transmitted to the drum 47 of the hoisting device through the sprocket-wheel 22, chain 23, sprocket-wheel 25, counter-shaft 24, gear 48 or 49, gear 50 or 51, shaft 52, which carries the gears 50 and 51, worm 53, on shaft 52, worm-gear 54, meshing with the worm 53, and spur-gears 55 and 56. The gear 55 is mounted on the shaft 57 which carries the worm-gear 54, and the spur-gear 56 is mounted on the shaft 58, which carries the drum 47. The worm 53 and worm-gear 54 are incased in a housing 59 and run in oil.

To obtain different speeds of the drum 47, I employ the gears 48, 49, 50 and 51. The

gears 50 and 51 are permanently secured to the shaft 52, while the gears 48 and 49 are carried by a sleeve 60 slideable upon the shaft 24, but keyed thereto so as to rotate therewith (see Fig. 4).

To shift the sleeve 60, I provide a shifting device consisting of the arms 61 and 62 pivoted at 63 to a block on the bed-plate 21, the arm 61 being provided with a pin 64 to engage an annular groove 65 in the sleeve 60 (see Fig. 4). When the gears 48 and 50 are meshed, the drum 47 will rotate at slow speed, because the gear 48 is smaller than the gear 50. When the sleeve 60 is moved to cause the gears 49 and 51 to mesh, the drum 47 will rotate at a higher speed, because the gears 49 and 51 are the same size. If desirable, the rotation of the drum can be controlled by the shifting-lever arms 61 and 62, for the reason that the gears 48 and 50 or gears 49 and 51 can be meshed or disengaged by shifting the sleeve 60. When this occurs, the driving gear 18 can be left in mesh with the gear 28 or gear 30, as the case may be.

Under ordinary conditions the gears 48 and 50 will be meshed, the throwing out operation occurring at the jack-shaft 19.

To automatically disconnect the hoist from the driving mechanism, or shaft 17, and its gear 18, I provide a cam disk 66 having a cam, teat or projection 67 (see Fig. 5) arranged to strike a roller 68 carried by an arm 69 pivoted at 70 to a bracket 71 on the bed-plate 21. The lower end of the arm or lever 69 carries a roller 72 which engages a jaw 73 in a slide 74 carried by a guide 75 on the bed-plate 21. At about the end of one revolution in either direction, the teat 67 will strike the roller 68 and move the arm to shift the sleeve 26 to the neutral position, at which time the drum 47 will cease rotating. For example, if the sleeve 26 is moved to the right (Fig. 10) to cause the gears 18 and 28 to mesh, the roller 68 on the arm 69 (Fig. 5) will be moved toward the left. At about the time the disk 66 has completed one revolution, the teat 67 will strike the said roller and move it toward the right until the gear 28 leaves the gear 18, at which time the drum will stop; the same action occurs during a reverse movement.

Under normal conditions the disk 66 will rotate with the drum 47, but said disk is not permanently secured to the shaft 58. To cause the disk 66 to rotate with the shaft 58 or to be disconnected therefrom, I provide a clutch-cone 76 to engage a cup 77 on the disk 66 (Fig. 3), the cone 76 being slideable upon but rotatably connected to the shaft 58 by a feather or spline 78. To shift the cone 76, I provide a shifting-lever 79 pivoted at 80 to a block 81 on the bed-plate 21. A spring 82 keeps the cone 76 and cup 77 in engagement. Should I desire to have the drum operate continuously for a space

of time, I would operate the lever 79 and disconnect the disk 66 from the shaft 58, at which time the automatic throwing-out mechanism would not operate; but as soon as the cone and cup become again engaged, the throw-out mechanism will operate after the teat 67 had sufficiently moved the lever 69. By this means the operation of the hoist is not limited to one revolution. For trailer hoisting purposes, one revolution would probably be sufficient, but should I need a little more, I would simply release the clutch, then cause it to again engage the disk; in the meantime, the drum 47 will have gained a little in rotation. In other words, the operation of the automatic release can be delayed by operating the clutch releasing mechanism.

What I claim as my invention is:

1. In a power-hoist, a drum, a shaft for said drum, means to operate same, a cam-disk carried by said shaft, a cam or teat carried thereby, a slide operable by said cam or teat and means carried by the slide 20 to disconnect the operating means after said drum has been operated to a predetermined extent.

2. In combination with the driving shaft of a motor vehicle, a gear carried thereby, a jack-shaft adjacent thereto, gears slidably mounted upon said jack-shaft but rotatably connected thereto, a hoisting drum, operating means connecting the said jack-shaft and said drum, a cam-disk operable with 30 said drum, and means operable by said cam-disk to operate the shifting means for the gears on said jack-shaft.

3. In combination with the driving shaft of a motor vehicle, a gear carried thereby, a jack-shaft adjacent thereto, gears slidably mounted upon said jack-shaft but rotatably connected thereto, a hoisting drum, operating means connecting the said jack-shaft and said drum, a cam-disk operable with 40 said drum, means operable by said cam disk to operate the shifting means for the gears on said jack-shaft, and means to delay the operation of said shifting mechanism by said cam-disk.

4. In combination with the driving shaft of a motor vehicle, a gear carried thereby, a jack-shaft adjacent thereto, gears slidably mounted upon said jack-shaft but rotatably connected thereto, a drum, a shaft 50 therefor, operating means connecting the jack-shaft and the shaft of said drum, a cam-disk loosely mounted on said shaft, a cam carried thereby, a releasable clutch connecting said shaft and said cam-disk, and

means operable by the cam on said disk to shift the gears on said jack-shaft.

5. The combination of a driving shaft, a gear carried thereby, shiftable gears rotatably mounted adjacent the gear first named 60 and arranged to mesh therewith, a jack-

shaft for said gears, means to shift said gears, a hoisting drum, a worm-gear to rotate same, a worm in mesh with said worm-gear, a shaft for said worm-gear, spur gears carried by said shaft, a counter-shaft adjacent thereto, gears slidably mounted on said counter-shaft arranged for rotation therewith, means to shift said gears to cause any two of the said gears to mesh, and means connecting said counter-shaft and jack-shaft.

6. The combination of a power shaft, a hoisting drum, a worm-gear to rotate same, a worm meshing with said worm-gear, a shaft for said worm-gear, a plurality of 80 spur gears of different diameters carried by said shaft, a counter-shaft adjacent thereto, a plurality of gears of different diameters slidably mounted on said counter-shaft, means to shift said slidable gears to cause 85 any one of the gears on the counter-shaft to mesh with a corresponding gear on the worm-shaft, and means connecting said counter-shaft and power-shaft.

7. The combination of a driving shaft, a gear carried thereby, shiftable gears rotatably mounted adjacent the gear first named and arranged to mesh therewith, a jack-shaft for said gears, means to shift said gears, a hoisting drum, a worm-gear to rotate same, a worm in mesh with said worm-gear, a shaft for said worm-gear, spur gears carried by said shaft, a counter-shaft adjacent thereto, gears slidably mounted on said counter-shaft arranged for rotation therewith, means to shift said gears to cause any two of the said gears to mesh, means connecting said counter-shaft and jack-shaft, and means controlled by the rotation of said drum to automatically shift the gears on the 100 jack-shaft.

8. The combination of a driving shaft, a gear carried thereby, shiftable gears rotatably mounted adjacent the gear first named and arranged to mesh therewith, a jack-shaft for said gears, means to shift said gears, a hoisting drum, a worm-gear to rotate same, a worm in mesh with said worm-gear, a shaft for said worm-gear, spur gears carried by said shaft, a counter-shaft adjacent thereto, gears slidably mounted on said counter-shaft arranged for rotation therewith, means to shift said gears to cause any two of the said gears to mesh, means connecting said counter-shaft and jack-shaft, a 110 cam-disk rotatable with said drum, a cam carried thereby, and means operable by the cam on said disk to shift the gears on said jack-shaft.

9. The combination of a driving shaft, a gear carried thereby, shiftable gears rotatably mounted adjacent the gear first named and arranged to mesh therewith, a jack-shaft for said gears, means to shift said gears, a hoisting drum, a worm-gear to ro- 125

tate same, a worm in mesh with said worm-gear, a shaft for said worm-gear, spur gears carried by said shaft, a counter-shaft adjacent thereto, gears slidably mounted on 5 said counter-shaft arranged for rotation therewith, means to shift said gears to cause any two of the said gears to mesh, means connecting said counter-shaft and jack-shaft, a cam disk rotatable with said drum; 10 a cam carried thereby, a lever arranged to

be operated by said cam and means operable by said lever to shift the gears on said jack-shaft.

Signed at New York city, N. Y., this 16 day of October, 1916.

SAMUEL STIMMEL.
